Primary Examiner — Stacia A Cadmus(74) *Attorney, Agent, or Firm* — Fish IP Law, LLP;
 Joseph A. Andelin(57) **CLAIM**

I claim the ornamental design for a wheel rim, as shown and described.

DESCRIPTION

FIG. 1 is a front elevation view of a wheel rim of the new design; and,

FIG. 2 is a top, front, right side perspective view thereof. The broken lines depicting portions of the wheel rim form no part of the claim.
